WIRES DRAWING MACHINE

Samuel Hugh Richards, Harpenden, England

Application January 5, 1934, Serial No. 705,370
In Great Britain January 5, 1933

6 Claims. (Cl. 205—16)

This invention relates to wire drawing machines and has for its object to provide an improved arrangement of the dies and associated parts in such machines which shall facilitate the operations of threading the dies and also enable a simpler construction of die box to be utilized.

In wire drawing machines as previously constructed the stepped pulleys have been rotated in the same direction as each other and either one set of dies has been employed, disposed on one side of the plane containing the axes of the two pulleys, or two sets of dies have been employed, disposed one on each side of the said plane.

When two sets of dies are employed the two die boxes are, in virtue of the position which they must occupy with relation to the stepped drawing pulleys, disposed comparatively closely one above the other and great difficulty is experienced in threading the dies of each box satisfactorily.

According to this invention, therefore, there is provided a wire drawing machine which is primarily characterized by the fact that the stepped drawing pulleys of each wire-drawing unit are driven in opposite directions, the adjacent runs of the wire extending between the pulleys crossing each other at points disposed approximately midway between the latter.

By this means it is possible to arrange two sets of dies in one die box and the invention also consists in such an arrangement and in other features of construction which will appear from the following description of one way in which the invention may be carried into effect, reference being had to the accompanying drawings wherein:—

Figure 1 is a plan view of the drawing pulleys of a twelve draft wire-drawing unit according to this invention, showing the dies and die-holders and their associated parts.

Fig. 2 is a diagrammatic end elevation thereof, the dies and the like being omitted.

Fig. 3 is a detail, fragmentary perspective view of a portion of the die holder.

Fig. 4 is a sectional elevation thereof.

Fig. 5 is a fragmentary end elevation, partly in section, showing lubricant supply means.

Fig. 6 is a corresponding plan view, partly in section,

Fig. 7 is a detail view, in sectional side elevation, of means for reciprocating the die holder, and

Fig. 8 is a sectional plan view thereof.

The twelve draft wire-drawing unit shown comprises two drawing pulleys 1 and 2 each having six steps (see Figs. 1 and 2) and mounted at a suitable distance apart. The stepped pulleys 1 and 2 are driven in opposite directions by suitable means

(not shown) at the requisite speeds and the runs of wire extending therebetween are so passed around the pulleys (see Fig. 2) that the adjacent runs cross each other approximately on a line parallel with the axes of the pulleys and midway between same.

The wire 3 to be drawn enters the unit, in the usual way, over a guide pulley 4 and passes upwardly through the first die 5a to the step 2a of smallest diameter on the first drawing pulley 2, 10 passing around this and leaving the underside thereof to pass upwardly to the second die 5b. From this the wire passes around the smallest step 1a of the second drawing pulley 1 and leaves the underside thereof to pass upwardly to the third 15 die 5c. From this the wire passes around the second smallest step 2b of the first pulley 2 to pass upwardly through the fourth die 5d to the second smallest step 1b of the second pulley 1 and so on until the run 3a of the wire leaving the underside 20 of the largest step 1f on the second pulley 1 is reached.

As will be understood this run 3a may either be passed over a guide pulley 6 to a further drawing unit or units or spooled, dependent on the gauge 25 of wire which is to be produced.

Owing to the arrangement above described the dies of each set, i. e. that set 5b, 5d, 5f, 5h, 5j, and 5l through which the wire passes upwardly from the first drawing pulley 2 and that set 5a, 5c, 5e, 30 5g, 5i and 5k, through which the wire passes upwardly from the second drawing pulley 1, are disposed at substantially the same level, the two sets being disposed on opposite sides of the vertical plane containing the points of intersection of 35 the adjacent runs of the wire.

Due to the arrangement shown and described, it is not necessary to relatively step or vertically offset the dies of either set correspondingly with the steps of the pulleys, and not only is manufacture therefore facilitated, but a stronger and more rigid machine may be produced, and one which may be more easily threaded.

Hence a single die box is provided to carry both sets of dies, referred to generally as the dies 5, 45 for convenience of description, and the construction of this box is preferably as follows:—

Each die 5 is mounted in a block 7 formed with a spindle-like extension 8 which is of larger diameter adjacent the block than it is over the 50 rest of its length and this portion of larger diameter is screw-threaded at 8a (Fig. 4) to be capable of being threaded engaged in a bearing boss 9a formed on one end of a pipe clip 9, the other end of the pipe clip 9 carrying a second 55

bearing boss 9b which is bored to receive the narrower portion of the extension 8.

The latter projects beyond the said second boss 9b and is screw-threaded at 8b to receive a nut 10 which serves simultaneously to lock the die block 7 in any desired position of angular adjustment attained by screwing the spindle 8 into or out of the first boss 9a on the pipe clip 9 and also to tighten the latter on to a tubular member 11 serving to carry the two sets of dies 5.

This tubular member 11 is arranged between the drawing pulleys 1 and 2, parallel with the axes thereof, and the dies of each set are disposed thereon in the manner above indicated by means of the pipe clips 9, it being possible to adjust each die 5 separately to the correct position, by shifting the clip 9 both longitudinally and circumferentially of the tubular member 11 and by screwing the spindle 8 into or out of the first boss 9a on the clip, this latter operation serving to adjust both the height and angular position of the die with respect to the path of the wire reach which it is to engage.

In order to lubricate the runs of wire as they enter the dies it is preferred to utilize the tubular member 11 as a lubricant conduit, the one end thereof being closed and the other being connected to a supply of lubricant as by a right-angle bend 12 (Fig. 8) and a flexible tube 13 (Fig. 5).

When very fine wires are being drawn it is necessary to prevent any lubricant adhering to the surfaces of the drawing pulleys and to this end the lubricant is only supplied to the runs of wire as they enter the dies which latter act to remove all lubricant from the wires as they pass therethrough.

For this purpose the end of the flexible tube 13 connecting the tubular member 11 to the supply of lubricant is preferably arranged to open into the lower end of a tank or container 14 (Figs. 5 and 6) to which the lubricant is supplied by suitable means, such as a pump 15 having its inlet pipe 16 regulatable by a cock 17, and a suitable head of lubricant is maintained in the tank, by any known means such as an overflow pipe 18, above the level of the uppermost portion of the outer surface of the tubular member 11, the latter being pierced with holes 11a at intervals along its length (see Figs. 3, 4 and 6) so that one hole is disposed beneath each run of the wire.

Due to the head of lubricant in the tank 14 the lubricant issues from each of the holes 11a in the tubular member 11 in the form of an upwardly directed fountain (indicated at 11b in Fig. 5), through the tip of which the corresponding run of wire is arranged to pass. To provide clearance for these fountains of lubricant the pipe clips 9 are formed with circumferentially elongated apertures 19 at suitable points so that the holes 11a in the tubular member 11 are never obstructed by the clips no matter what the position of adjustment thereof.

The lubricant flowing downwardly around the exterior of the tubular member 11 drips into a gutter or trough 20 disposed longitudinally beneath the latter and is conducted thereby to a pipe or conduit 21 leading to a sump 22 from which the lubricant is again returned to the tank 14 by means of the pump 15.

When the dies 5 are to be reciprocated to prevent grooving of the drawing pulleys 1 and 2 by hard wires it is preferred to reciprocate the

whole unit comprising the tubular member 11 and the dies 5.

Means for producing this reciprocation are shown in Figs. 7 and 8, where 23 is a heart-shaped cam mounted on a shaft 24 adapted to be driven from some suitable part of the wire-drawing machine proper to oscillate a two-armed lever 25, 25a, the arm 25 of which carries a roller 26 bearing on the periphery of the cam 23. The arm 25a of the two-armed lever is formed with a screw-threaded aperture in which is engaged an adjustable screw 27 adapted to be locked in any position of adjustment by means of a lock-nut 28 and formed at its inner end, adjacent the tubular member 11, with a nose or pin-like extension 27a adapted to be received in a conical recess 29 formed in the end of a thrust-rod 30 of which the other end is similarly formed with a conical recess 31 taking over a pin 32 projecting from the rear face of a plate member 20 33 secured on the corresponding end of the tubular member 11.

Said plate member 33 extends laterally from the tubular member 11 to carry a guide pin 34 adapted to slide longitudinally in the aperture 25 of a guiding boss or bearing 35 on the stationary plate 36 of the machine, the tubular member 11 also being slideable longitudinally through a boss or bearing 37 on said plate.

The parts 29, 30 and 31 are maintained in engagement by means of a spiral tension spring 38 connected between the plate member 33 and the upper arm 25a of the two-armed lever 25, 25a, and the return motion of the tubular member 11 is ensured by means of a tension spring 39 connected between a pin 40 projecting from the right-angle bend 12 on the end of said member 11 and a pin 41 mounted on the framing portion 42 of the machine.

It will be seen that the rotation of the cam 23 produces longitudinal reciprocation of the tubular member 11, and hence of the dies 5 mounted thereon, and that adjustment of the screw 27 causes bodily displacement of the shaft 11 along its line of reciprocation to cause it to reciprocate in a different zone, and therefore, enables the path through which the dies reciprocate to be displaced axially as a whole relatively to the drawing pulleys 1 and 2. The heart shape of the cam prevents the wire from dwelling at each end of the path on which it is reciprocated through the instrumentality of said cam. Heretofore, such dwelling has existed resulting in grooving of the drawing pulleys.

The sizes of the holes 11a in the tubular member 11 are preferably such that a substantially uniform height of the fountains of lubricant is ensured, in spite of the friction between the lubricant and the inner wall of the tubular member through which it flows.

In machines intended to draw wires of comparatively heavy gauge, however, it is usual to provide a copious flow of lubricant which is allowed to reach the drawing pulleys 1 and 2 and fills the whole of the space containing the drawing unit with fine spray when the pulleys are revolving, it being understood that this space is provided with a liquid-tight cover when the machine is in operation.

For such machines, when constructed in accordance with this invention, the lubrication is preferably again effected by means of the tubular member as indicated above, the open end of the said member being, in this case, supplied with lubricant under pressure by suitable means and

the holes formed in the upper portion thereof being adapted to direct jets of lubricant directly into mouths of the dies.

5 The lubricant tank and the gutter or trough are dispensed with and the excess lubricant may be allowed to collect in a sump in the space containing the drawing unit, from which it is or may be returned by a pump to the tubular member.

10 If desired, supplementary apertures may be formed laterally of the tubular member for directing additional jets of lubricant directly on the revolving drawing pulleys.

15 When threading up the dies the pressure of the lubricant is preferably reduced, for example, by means of a valve-controlled by-pass.

It will readily be understood that the die box may be reciprocated longitudinally in this form of the invention also, if required.

20 Owing to the arrangement of the dies 5 in a die box comprising a tubular member 11 which is straight and horizontally disposed, the outer end of the said die box may be provided with a suitable bearing 43 (Fig. 6) to prevent vibration or whipping of the die box and this bearing may, of course, be suitably arranged to allow of the requisite longitudinal reciprocation of the die box when required.

I claim:—

25 1. In a wire-drawing machine, a plurality of dies for wire reaches, a tubular shaft carrying said dies and having perforations for discharging oil onto said reaches, a rigidly mounted trough under said shaft to receive the oil discharged through said perforations, said trough having bearings at its ends in which said shaft is mounted, and means for feeding oil into said shaft and for returning the oil from said trough into said shaft.

30 2. In a wire drawing machine, drawing pulleys on parallel axes, drawing dies, a support to which said dies are secured, said support being mounted for reciprocation on a line parallel with the pulley axes, and reciprocating means for said support including a thrust device engaging said die support and adjustable to bodily displace said die support along its line of reciprocation to cause said support to reciprocate in a different zone, thereby causing engagement of the wire with different portions of the pulleys when desirable.

35 3. In a wire drawing machine, drawing pulleys on parallel axes, drawing dies, a support to which

said dies are secured, said support being mounted for reciprocation on a line parallel with the pulley axes, and reciprocating means for said support including a thrust rod having one end engaged with said support, a lever having an adjusting screw engaged with the other end of said thrust rod, and a cam for oscillating said lever to reciprocate said thrust rod and die support, said adjusting screw being substantially in alignment with said thrust rod and being operative to bodily displace said die support along its line of reciprocation to cause said support to reciprocate in a different zone, thereby causing engagement of the wire with different portions of the pulleys when desirable. 15

4. In a wire drawing machine, a die block having a spindle, a cylindrical support at right angles to said spindle, a clip surrounding said support and turnable circumferentially thereon, said clip having bearing means in which said spindle 20 is received for turning about its longitudinal axis, and means for normally holding said clip against turning on said support and said spindle against turning in said bearing means.

5. In a wire drawing machine, a cylindrical 25 support, a transversely split clip surrounding said support and turnable circumferentially thereon, the ends of said clip being provided with lateral bosses, said bosses having aligned bearing openings, a die block having a spindle passing through 30 said openings and capable of lengthwise and turning adjustment therein, and means for normally holding said spindle against movement in said openings and for holding said clip tightly contracted upon said support. 35

6. In a wire drawing machine, two stepped oppositely rotatable drawing pulleys between which the wire extends in crossed reaches, an elongated cylindrical support parallel with the pulley axes and disposed near the crossing points of the wire 40 reaches, clips adjustably mounted on said support for turning adjustment circumferentially of the same and for adjustment longitudinally thereof, and die-supporting spindles adjustably mounted on said clips and disposed at right angles to the length of said support, said spindles being adjustable in the directions of their lengths and being turnably adjustable about their longitudinal axes, and means for holding said clips and said spindles in adjusted positions. 45

50 SAMUEL HUGH RICHARDS.
